UNITED STATES PATENT OFFICE.

IVAR HJALMAR SVALIN, OF MOTALA VERKSTAD, SWEDEN.

INTERNAL-COMBUSTION ENGINE.

1,129,316.

Specification of Letters Patent. Patented Feb. 23, 1915.

Application filed February 26, 1913. Serial No. 750,839.

To all whom it may concern:

Be it known that I, IVAR HJALMAR SVALIN, a subject of the King of Sweden, and resident of Motala Verkstad, in the 5 Kingdom of Sweden, have invented certain new and useful Improvements in Internal-Combustion Engines, of which the following is a specification, reference being had therein to the accompanying drawing.

10 Hitherto, in one type of internal combustion engines ignition has been effected, after the state of continuation has entered, by a special ignition device, such as a flame, a hot tube or an electric spark. In another 15 type of such engines no special device is used for said purpose, this being for instance the case in Diesel motors, where ignition is effected by the heat of compression, and in the ignition chamber motors. On account 20 of the high compression necessary in the Diesel motors thick shafts, bearings, crank rods and a great strength of the material are wanted, which, apart from the other expensive arrangements, renders such motors 25 necessarily very dear. The ignition chamber motors, on the contrary, offer the advantage that ignition can be effected at a low pressure, such motors being, however, affected with the inconvenience that it is 30 only at a certain loading that they ignite well and that the motor works economically. At a lower loading the ignition chamber will be cooled, whereby the combustion will be 35 incomplete and the running of the motor irregular. At a higher loading, on the other hand, the ignition chamber will become too hot, so that advanced ignitions are caused, whereby the efficiency of the motor is diminished.

40 The present invention now refers to a combustion chamber provided with a mixing, gasifying and ignition device (in the following specification called mixer) which, after having been heated on starting the 45 motor, will not be cooled when the motor is running light, and which will not become too hot at the maximum loading of the motor, whereby, under all loading circumstances, an economical combustion is obtained 50 during which the combustion chamber will be perfectly free from any deposits of soot and coke. However, the said device

admits of the employment even of the cheapest oils of very low volatility.

The invention is illustrated on the accompanying drawing, where—

Figure 1 is a vertical longitudinal section of the combustion chamber and the mixer, and Fig. 2 is a horizontal cross section of the same. Figs. 3 and 5 are vertical sections through modified forms of the mixer, and Figs. 4 and 6 respectively are horizontal cross sections of the same.

The combustion chamber 1, which may have a cylindrical, spherical or other suitable shape, is surrounded by a water jacket 8 and separated from the cylinder 10 by means of a partition wall 7. The mixer passing through the combustion chamber 1, opens into the cylinder at the central part of 65 said wall 7. During the compression stroke of the piston air is forced into the mixer 2, through the holes 6 provided in the walls of the same and then into the combustion chamber 1. At the same time combustible 70 is forced into the mixer through the opening 3, whereby a jet of combustible is forced downward axially through the mixer 2, said combustible being thereby vaporized by the heat radiating from the walls of the same. 75 Thus, in the tube shaped chamber of the mixer an axial jet of combustible meets with a current of air passing in the opposite direction partly axially and partly along a spiral curve 9, so that a rotary or whirling 80 movement is imparted to the same. The whirling movement can also be effected in other ways, as is further described below in connection with Figs. 3-6. In this manner a thorough mixing is effected, and one 85 part of the air-gas mixture is forced laterally through the openings 6 into the chamber 1. Immediately before the piston arrives at the upper dead center the gas mixture in the mixer 2 is ignited by the heat 90 radiating from the walls of the same, and the ignition rapidly and uniformly propagates in all directions through the openings 6 to the mixture poor in combustible and contained within the chamber 1, so that the 95 combustion will be complete. In the above mentioned partition wall 7 holes or openings 5 are provided, and through said holes or openings air is forced from the cylinder 100

during the compression stroke. The currents of air thus produced meet with and penetrate the currents of air-gas mixture coming from the openings 6, thereby effecting a very intimate mixing of air and gas.

After the ignition has taken place the products of combustion will pass through the openings 6, the mixer 2 and through the opening 4 into the cylinder 10. By means of 10 the excess of air, the soot and dust which may have deposited in the mixer 2 at the high temperature in question, will burn so that said mixer becomes perfectly clean. At 15 the same time the walls of the mixer will absorb the heat required for the subsequent gasifying and ignition and, thus, the same will also act as a regenerative ignition device. At the same time during the expansion, one part of the gas will pass through 20 the openings 5 directly into the cylinder instead of passing through the mixer. Thereby a suitable temperature can be imparted to the mixer depending on how great quantity of the gas is passing through the openings 6 in relation to that of the openings 5. The combustible is forced in at 3 by a pressure as by a pump or the like. The mixture of the combustible with the air forced into 25 the mixer 2 through the opening 4 during the compression stroke of the motor takes place during the last portion of the compression stroke. As the chamber 1 forms the whole combustion chamber all combustion air must pass through the mixer 2 and 30 its holes 6 and through the holes 5 during the said stroke in order to reach the combustion chamber 1. No combustion takes place in the cylinder 10 but only expansion. The ignition is effected in the mixer 2 and 35 on account of the high pressure occurring there the gas mixture contained in the mixer and which has not already been forced out during the compression stroke through the holes 6 of the chamber 1, is thrown out into the said chamber containing poorer gas mixture, whereby an intensive and uniform mixing of poorer and richer mixture is effected which burns rapidly in the combustion chamber. During the compression 45 stroke the current of air passing through the holes 5 is encountering the current of gas passing through the holes 6, whereby a poor but well mixed gas-air-mixture is formed in the combustion chamber 1 before 50 the ignition moment. When the ignition is beginning in the mixer 2 a further mixing of gas with the mixture contained in the chamber 1 is effected as has been described above, the ignition being propagated uniformly to all parts of the chamber 1. At 55 the start the mixer or chamber 2 is first heated some minutes and then it will remain hot enough for vaporizing and igniting the fuel by the heat supplied by the explosions. 60 When the piston compresses the air in the 65

cylinder 10 during the compression stroke there is in said cylinder a higher pressure than in the combustion chamber 1 and thereby the air is forced to pass through the mixer 2 and its openings 6 and through the opening 5 out in the chamber 1. The relations of the quantity of air passing through the mixer 2 and the opening 6 and the openings 5 depend on the relative size of the openings in question, the difference of the 70 pressure in the cylinder 10 and the chamber 1 being not greater than to correspond to the resistance of the current in the openings.

Figs. 3 and 4 show a modified form of the mixer. The latter here consists of a 80 cylinder 11 in which there is provided a number of horizontal partition walls 16, each wall being provided with a central opening 12 and with openings 13 located on each side of said central opening. In every 85 other wall the openings 13 occupy the position indicated with full lines in Fig. 4, and in the remaining walls said openings occupy the position indicated with dotted lines in said figure. By this means gas and air 90 will have to pass along a zigzag formed way, whereby they are intimately mixed together.

According to Figs. 5 and 6 the cylinder 11 is also provided with horizontal partition walls 17, said walls, however, do not extend 95 all over the width of the cylinder, but only for a distance beyond the central line of the same. These walls are also provided with holes 18 lying in the central line of the cylinder. Other modifications may also be 100 made within the scope of the present invention.

Having now described my invention, what I claim as new and desire to secure by Letters Patent is:

105

1. In internal combustion engines the combination with the mixing-vaporizing-and igniting devices and the combustion chamber separated from the cylinder, of a tube-shaped mixer located centrally in the 110 combustion chamber, means for supplying air and combustible into opposite ends of said mixer means within the passage of said mixer for intimately mixing air and combustible, and radially located openings in 115 the walls of the mixer between the passage in the same and the surrounding combustion chamber, substantially as and for the purpose set forth.

2. In internal combustion engines the 120 combination with the mixing-vaporizing-and igniting devices and the combustion chamber separated from the cylinder, of a tube-shaped mixer located centrally in the 125 combustion chamber, means for supplying air and combustible into opposite ends of said mixer, the passage in said mixer being spiral-shaped for imparting rotary movement to the air and gas and thereby intimately mixing air and combustible, and 130

- radially located openings in the walls of the mixer, said openings leading from the bottom of the spiral in the mixer, substantially as and for the purpose set forth.
- 5 3. In internal combustion engines the combination with the mixing—vaporizing—and igniting devices and the combustion chamber separated from the cylinder, of a tube-shaped mixer located centrally in the
- 10 combustion chamber, means for supplying air and combustible into opposite ends of said mixer, the passage in said mixer being spiral-shaped for imparting rotary movement to the air and gas and thereby intimately mixing air and combustible, and
- 15 radially located openings in the walls of the

mixer, said openings leading from the bottom of the spiral in the mixer, a partition wall between the cylinder and the combustion chamber, and openings in said partition wall, said openings being of such size that the air partly passes through the said openings without striking the mixer, substantially as and for the purpose set forth.

In witness whereof, I have hereunto signed my name in the presence of two subscribing witnesses.

IVAR HJALMAR SVALIN.
